UNITED STATES PATENT OFFICE.

HENRIK HILLBOM, OF WALLINGFORD, CONNECTICUT, ASSIGNOR TO
R. WALLACE & SONS MFG. CO., OF WALLINGFORD, CONNECTICUT, A CORPORATION.

DESIGN FOR A TEAPOT OR SIMILAR ARTICLE.

No. 38,070.

Specification for Design.

Patented June 12, 1906.

Application filed May 7, 1906. Serial No. 315,672. Term of patent 14 years.

To all whom it may concern:

Be it known that I, HENRIK HILLBOM, a citizen of the United States, residing at Wallingford, in the county of New Haven and State of Connecticut, have invented a new, original, and ornamental Design for a Teapot or Similar Article; and I do hereby declare the accompanying drawing to be a full, clear, and exact illustration of the same, and which said drawing constitutes part of this specification, and represents a side view of a teapot embodying my design.

I claim—

The ornamental design for a teapot or similar article, as shown.

HENRIK HILLBOM.
